UNITED STATES PATENT OFFICE.

WILLIAM H. SAWYER, OF PROVIDENCE, RHODE ISLAND, ASSIGNOR OF
ONE-HALF TO EUGENE F. PHILLIPS, OF SAME PLACE.

TELEPHONE-SWITCH.

SPECIFICATION forming part of Letters Patent No. 242,698, dated June 7, 1881.

Application filed February 3, 1881. (No model.)

To all whom it may concern:

Be it known that I, WILLIAM H. SAWYER, a citizen of the United States, residing at Providence, in the county of Providence and State of Rhode Island, have invented certain new and useful Improvements in Telephone-Switches; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

15 My invention relates to a switch-board or switching apparatus of the group and table plan, for use in the central office of a telephone-exchange system to connect the different subscribers' circuits for the purpose of oral communication. Its object is to provide simple and ready means for making the necessary connections for communication between the subscribers of the different circuits grouped or arranged on any one table with others of 25 the same group, or with those of any other group or table of the exchange system, and to effect such connections without the use of the ordinary removable flexible cords, which have proven to be extremely inconvenient and embarrassing in the manipulation of the switch systems now in use.

In my switching apparatus I use any number of switch boards or tables, each comprising any convenient number of sections, each 35 of which includes a circuit terminal annunciator and devices for signaling and connecting the circuit with the operator's telephone and other points of the system. I preferably arrange fifty sections upon a single board or table, that having been found by experience to be a convenient number, and all the devices requiring to be manipulated in connection with any particular line are arranged in the same section and adjacent to each other, so that the 40 hand of the operator readily passes from one to another without the trouble of selecting them separately from groups or series of devices of a similar nature, as is the case, more or less, in the telephone-switch systems here- 45 tofore invented.

My invention will be readily understood from the following particular description, in connection with the accompanying drawings, in which—

Figure 1 is a front elevation of a switch-board constructed according to my invention. Fig. 2 is a perspective view of a single section. Fig. 3 is a view of the board behind said section. Fig. 4 is a section on line *x x*, Fig. 3. Fig. 5 is a front view of a board with twelve 60 sections. Fig. 6 is a perspective view of the switch for connecting tables. Fig. 7 is a view, in front elevation, of two tables, each having only nine sections, the tables being shown of this small capacity to avoid confusion in showing the various connections. Fig. 8 illustrates a modified form of table-connecting switch. Fig. 9 is a view of one of the plugs.

The letter A, referring now particularly to Fig. 2, indicates the supporting-board, and B the annunciator-drop, which is shown in its upright position. This drop is thrown down to expose its opposite side, which is inscribed with the number of the line or circuit by the operation of the armature C of an electromagnet, C', arranged in an aperture in the board, and having its core behind the armature, as indicated in dotted lines. The line-wire is normally connected to the ground through the helix of the magnet, as will presently be described.

The letter D designates a strip of metal secured to the face of the board, and upon each side of said strip, and separated therefrom and from each other, are five small metal plates, 85 E' E² E³ E⁴ E⁵ and F' F² F³ F⁴ F⁵. At the upper and lower ends of the strip are similar small plates, (lettered G and H, respectively,) and between each small plate and the strip D there is formed a socket, to permit the insertion of 90 a wedge-like spring-plug, such as shown in Fig. 9, such plugs being used to connect the small plates and the strip D electrically, in the ordinary manner.

To the front face of the plate G is pivoted 95 one end of an elastic metallic arm, I, the other end of which extends behind the laterally-projecting portion of a metallic bracket, K, which is secured to the board A, the arm being so arranged that its tip normally bears outward 100

- against said bracket, but by pressing upon a knob, *i*, may be forced inwardly in contact with a metal plate, *L*, secured to the board behind the laterally-projecting portion of the bracket.
- 5 The arm *I* may be swung laterally on its pivot to bring its tip in front of either of two metal plates, *M* or *N*, both of which are secured to the board and respectively on opposite sides of the normal position of the arm.
- 10 The letter *O* designates a push-button, the shank of which, as shown in Fig. 4, extends loosely through a hole in the board and terminates on the rear side thereof in a button, *o*, of some non-conducting substance, such as 15 hard rubber. Against the rear surface of this button *o* lie the separated tips of two flat metal springs, *P* *P'*, (shown in dotted lines in Fig. 2 and full lines in Figs. 3 and 4,) the other ends of which are secured to the back of the board.
- 20 Directly in rear of the free tips of the springs *P* *P'*, and separated a little distance therefrom, stand the free ends of two other flat metal springs, *Q* and *Q'*, the opposite ends of which are secured to the board, and intermediate portions of which rest upon metal plates *R* *R'*, which are connected by a wire, *r*.
- 25

The electric circuit, in the normal condition of the apparatus, is established from the line-wire (numbered 10) to spring *Q*, over said 30 spring, plate *R*, wire *r*, plate *R'*, spring *Q'*, a wire, 15, (indicated by dotted line,) plate *H*, a plug, *S*, strip *D*, a plug, *S'*, plate *G*, arm *I*, bracket, a wire, 20, (shown by a dotted line as leading from the said bracket to the magnet-helix,) over said helix and a wire, 25, to the ground.

The springs *P* and *P'* are respectively connected, by wires *p* and *p'*, with metal strips *t* and *t'*, secured to the board, and respectively 40 connected with the opposite connecting-posts of a receiving-telephone, *T*, and also with the opposite connecting-posts of a transmitter arranged behind the board, and having its mouth-piece *T'* projecting in front. The springs *P* and *P'* may be connected with the receiving and transmitting telephones in any other convenient manner.

The plate *L* is connected, by a wire, 30, with a magneto-electric generator, and the plates 50 *M* and *N* may be connected respectively with the opposite poles of a battery, the middle of which is connected with the ground in the usual manner of alternating batteries.

I have not described the annunciator in detail, as any convenient form may be used. The sections, of which, as before stated, I prefer to arrange fifty on one board, are precisely alike, the small plates *E'* are connected by suitable wires to the corresponding plates *E'* of all the 60 other sections, the plates *E'* to the plates *E'* of all other sections, and so on for the plates on both sides of the strip *D*, but not those at the ends.

The operation of the apparatus as thus far 65 described is as follows: When a subscriber at a station connected with the line desires to

communicate with another, he closes his battery-circuit or operates a magneto-electric call apparatus, as the case may be, and sends a current over the line, which causes the annunciator-drop to fall; observing which, the operator immediately presses upon the knob *i* and brings the tip of lever *I* in contact with plate *L*, thus switching the circuit to the magneto-electric generator, which is in the meantime 70 operated by the operator by means of a treadle, as usual. A current is thus sent over the line to ring the subscriber's bell and notify him that his call has been received. The operator then removes his finger from the knob *i* and places it 75 upon the push-button *o*, forcing said button inward, and causing the button *o* to press the springs *P* and *P'* into contact with the springs *Q* and *Q'* and the latter out of contact with the plates *R* and *R'*, thus looping into the circuit the 80 wires *p* *p'* and the receiver *T*, which the operator then places to his ear and hears the subscriber's directions as to whom he desires to talk to. Suppose this to be the subscriber on line No. 50. The operator now removes the 85 plug *S'* from between strip *D* and plate *G* and places it between said strip and plate *E'*, thus connecting the line No. 1 with said plate *E'*. He now calls the subscriber on line 50 by pressing upon button *i* of section 50, connecting the 90 line with the magneto-electric generator, and sending over it a current which rings the bell of the subscriber wanted. Subscriber 50 answers by sending a current which operates his annunciator, when the drop of which falls, the 95 operator removes the plug *S'* of section 50, places it between the small plate *E'* and strap *D* of that section. As the plates *E'* of all the 100 sections are connected, this connects line 50 with line 1, and the connections are as follows, viz: from line-wire of No. 1 over spring *Q*, plate *R*, wire *r*, plate *R'*, spring *Q'*, wire 15, plate *H*, plug *S*, strip *D*, plug *S'*, (which is now between strip *D* and plate *E'*,) plate *E'*, over the wires which connect all the plates *E'* 105 to plate *E'* of section 50, then at said section over the plug *S'* between said plate and adjacent strip *D*, over said strip, plug *S*, plate *H*, wire 15, spring *Q*, plate *R'*, wire *r*, plate *R*, spring *Q*, to line-wire of No. 50. Being thus 110 connected, the subscribers are left to converse, and by cutting in his transmitter and receiver, as before explained, the operator may either listen to or speak to them to ascertain when they have finished. A signal-bell may, however, be connected with each line, by means of which the subscribers may signify their discontinuance of conversation; or the annunciators might be placed in circuit between springs *Q'* and plates *H*, and used to notify the operator both of a desire to communicate and of 115 finishing. In Fig. 5, sections Nos. 1 and 12 are connected as described above for sections 1 and 50.

If while subscribers on lines Nos. 1 and 50 120 are conversing subscribers on any other two lines desire to communicate, the operation of

connecting will be the same as described for 1 and 50, except that, as the plates E' and their connecting-wires are already in use, the plugs must now be inserted between other small 5 plates, say E² and strips D, of the sections to be connected.

By plugging all the plates E', E², E³, E⁴, and E⁵, five distinct cross-connections may be made between ten different subscribers at the same time. This number of simultaneous connections has generally been found sufficient; but it is obvious that the plates F' F² F³ F⁴ F⁵ might be used for the same, though intended for another purpose, to be presently explained; 15 or the strips D might be extended and more small plates placed in the rows; or parallel strips, electrically connected, and additional rows of small plates might be used.

In case there are two subscribers on the same 20 line, one may be supplied by a bell-call operated by a current of a given polarity, and the other with a bell operated by a current of opposite polarity.

The plates M and N being connected to opposite poles of a battery, the middle of which is connected to the ground, the arm I may be placed in contact with either of said plates to cause a proper current to flow over the line to 25 actuate either bell. If more than two subscribers are on the same line, different numbers of impulses may be sent to ring different bells. Both "magneto-lines" and "battery-lines," as they are technically termed, may be grouped together on my switch-board.

35 I will now proceed to describe the devices by means of which sections of one group or board may be connected with others of another group or board.

All the small plates F' of the several sections are connected together by suitable wires, and the plate F' of the last section is connected, 40 by a wire, f', (see Fig. 5,) with a metal stud, upon which is pivoted a metal arm, U', (see, also, Fig. 6,) on the board below the sections, 45 said arm being arranged to swing round a circle and secured to its pivot with sufficient friction to prevent its moving when not required. The free end of the lever is bent outward and has in it a transverse slot, through which plays 50 a sliding metal plate, u, to the inner end of which is connected a rod, u', which plays through a hole in a lug, u², projecting from arm U'. Surrounding this rod is a spiral spring, which bears against the lug u² and the inner 55 end of plate u, forcing its outer end or tip normally outward beyond the end of the arm U'. A suitable knob is secured to plate u, for convenience in sliding said plate inward when desired. In the path described by the projected 60 tip of the plate u when it is swung around on its pivot, there are secured to the board five (in the present instance) small metal plates, (marked, respectively, 1 2 3 4 5,) and the tip of the plate u may be brought in contact with 65 any one of said plates; or, by sliding the plate inward, the arm may swing around and the slid-

ing plate avoid contact with all. There are five such arms, U', U², U³, U⁴, and U⁵, mounted upon the board, and provided with sliding plates arranged to come in contact with small stationary plates, as just described. Each arm and its sliding plate and contact-points constitute a table-connecting switch, and these switches are, for convenience, designated as switch No. 1, switch No. 2, and so on.

The plates F² of the sections are connected to arm U² by a wire, f², plates F³ to arm U³ by a wire, f³, and so the other sets of similarly-lettered plates are connected to the other switch-arms.

The plates F' F² F³ F⁴ F⁵, I term the "table-connecting plates," for a reason which will presently appear, and a set consists of those which are connected.

Now, let us suppose there are five switch 85 boards or tables in an exchange central office, and all alike, except that the sections of board No. 1 are numbered from 1 to 50, those of board No. 2 from 51 to 100, and so on by fifties. The switch contact points or plates 1 of switches 90 No. 1 of all the tables are connected by suitable wires, and so the other similarly-numbered plates of similarly-numbered switches are connected. The tables are numbered from 1 to 5. Should a subscriber on line No. 1, which is 95 connected with the table No. 1, desire to communicate with a subscriber on line No. 51, which is connected with table No. 2, he so notifies the central office, and the operator at table No. 1 proceeds precisely as described for 100 connecting two lines at the same table up to the point of changing plug S', and now, instead of placing said plug between plate E' and strip D, he places it between said strip and plate F', and then swings the arm of 105 switch No. 1, so that the sliding plate of said arm will come in contact with contact-plate 1 of that switch. He then notifies the operator at table No. 2 to connect his line No. 51 with point 1 of his switch No. 1. The operator at 110 table No. 2 then notifies subscriber on line 51, and proceeds to make the desired connection in the same manner as pursued by operator at table No. 1. As the points 1 of all the switches No. 1 are connected as before stated, the two 115 lines are now in communication, and the circuit is as follows, referring to Fig. 7, and regarding section 13 of table No. 2 in lieu of section 51, the table in this figure being made with a small number of sections to avoid confusion in the representation of the connections, and only such plate-connecting wires are shown as are in use: from line-wire No. 1, by the same route as heretofore described, to plug S', thence over plates F' and their 120 connecting-wires, and over wire f' to the pivot of switch-lever U', over said lever, its sliding plate, contact-plate 1, and wire y', to plate 1 of switch No. 1 of table No. 2, and from this plate to line-wire No. 13 by a route similar to 125 that followed from line No. 1 to point 1 of switch No. 1 of table No. 1.

In notifying operators to make connections between tables the card system is preferable. In the present case operator No. 1 would send by the office boy to operator No. 2 a card marked 51—1—1, signifying connect section 51 with point 1 of switch 1. If while the two subscribers are conversing another on a line connected with table No. 1 desires to communicate with a subscriber whose line connects with some other table, the connections are made in precisely the same way, except that the operator now uses the point No. 1 of another switch, (any one will answer,) and directs the operator at the other board to connect with point No. 1 of a correspondingly-numbered switch. The sliding plates u are to permit the switch-arms to be shortened while being moved, so as to avoid possible interference with connections by making contact with any except the desired plate. The plates or points 1 are solely for making connection from table No. 1, and are to be used only by the operator at that table and those whom he may direct to use them for making connection with his table. So all the points are for connections with correspondingly-numbered tables.

It is obvious that each table may be supplied with as many switches as desired, the number corresponding, of course, with the number of sets of table-connecting plates. When additional tables are added to the exchange additional points may be added to the switches. If there should be fifty tables, each with five switches, then each might be arranged to connect with five lines of every or any other or with five lines of any five of the fifty.

Each switch might have two or more switch-arms, if desired, their pivoted ends being electrically connected to a common support, and then either could be used for a given number of points comprised in a given arc of its movement. Thus the extent of movement required could be reduced.

It has been found that five connections with other tables are all that are necessary in practice. This would require five switches. However, as each switch could, if desired, contain one hundred points or plates, these five connections could be made with any five of one hundred tables or with any particular table of the one hundred; or an extension or wing, either at the side or lower edge, could be added to the table, and an additional series of five switches, each of one hundred points, arranged upon said extension or wing, each additional switch having its arm connected electrically with one of the first series, thus forming in effect a double switch of two hundred points, so that five connections could be made with two hundred tables. It is obvious that in the same manner the switches might be trebled or extended in capacity, as desired, without other change in the tables than adding one or more boards to afford room when necessary.

The object of plate H at the foot of strip D

and plug S is this: If the operator at a table (say No. 1) desire to make connection with a subscriber's line at another table, (say No. 2,) and the operator at the latter table is busy or absent, then (providing he has left, as he should have done, his switch-lever at switch 1 in contact with point 1, lever at switch 2 on point 2, and so on) operator at table No. 1 can, by removing plug S and placing it between strip D and plate E', throw off line No. 1 and connect line 51 with lever I at section No. 1 of table No. 1, and he can then himself, by pressing this lever on plate L, send a current from the magneto-electric generator to call up subscriber on line 80 No. 51.

In Fig. 8 I have illustrated a modified form of table-connecting switch which may be substituted for that before described.

The letters W' W^2 W^3 W^4 W^5 indicate metallic strips fixed to the board to take the places of the levers, and X' X^2 X^3 X^4 X^5 are contact-plates arranged alongside of but separated from the strips, and are to be connected respectively with corresponding plates on the other tables. Plugs like that shown in Fig. 9 are used to connect the strips and contact-plates. The strips are to be respectively connected with the different sets of table-connecting plates of the sections, as are the levers before described, and in practice the plates should be numbered as are the plates in the other form of switch.

In using this switch, instead of swinging a lever, a plug is simply inserted to connect the strip and desired plate.

I do not confine myself to any particular number of sets of section-connecting plates, table-connecting plates, or table-connecting switches, as it is obvious that the numbers may be varied without invention; nor do I limit myself to any particular manner or devices for connecting the receiver and transmitter with the subscribers' lines, as any of the known modes may be used. I may also use any known and suitable form of annunciator.

I do not claim as my invention the division and arrangement of subscribers' lines upon separate desks or switch-boards, each provided with complete apparatus for connecting the lines and serving subscribers whose lines may be grouped together, combined with open connecting-wires to be used in case it should become necessary to connect lines terminating at different switch-boards, as such a system has been used by others prior to my improvement.

What I claim is—

1. The combination, in a switch board or table, of a series of sections, substantially as described, each section consisting of an annunciator connected in a subscriber's circuit having a ground-connection, a series of metal contact-plates arranged adjacent to and for plug-connection with a common conductor included in said circuit, each contact-plate of each section being permanently in electrical connection with a serially-corresponding plate in every other section, and means for placing a tele-

phonic receiver in the circuit, and for disconnecting the circuit from its ground-connection, whereby a call may be received, the subscriber's wants ascertained, and any two circuits disconnected from ground and connected together by means of simple plugs, and without the use of detachable portable connecting devices.

2. In a telephonic-exchange switch system, 10 the combination of two or more switch boards or tables, each provided with a series of sections, substantially as described, each section consisting of an annunciator connected in a subscriber's circuit having a ground-connection, a series of metal contact-plates arranged adjacent to and for plug-connection with a common conductor included in said circuit, each contact-plate of each section being permanently in electrical connection with a 15 serially-corresponding plate of every other section, and with a switch arranged to connect a set of such connected plates with a similar switch and set of contact-plates upon another board or table, or any one of several other 20 boards or tables, and means for breaking the circuit ground-connections, whereby any subscriber's circuit terminating at any table may be readily disconnected from the ground and connected with any circuit terminating at any 25 other switch board or table in the exchange. 30
3. In a telephone switch-board, a series of terminal sections, each comprising an annunciator connected with a subscriber's line and with the ground, shunting devices arranged to 35 cut the telephone into the line-circuit, a switch arranged to disconnect the line from the ground and connect it with an electrical generator, and a series of contact-plates arranged adjacent to and for plug-connection with a common conductor included in the line-circuit, each of said 40

plates being permanently in electrical connection with a serially-corresponding plate in every other section, whereby are arranged in compact form for convenient and rapid manipulation all the devices essential to receiving calls, 45 ascertaining subscribers' wants, disconnecting line-circuits from the ground and connecting them together.

4. The combination, with each of a series of switch boards or tables, each provided with 50 line terminal sections and permanently-connected sets of contact-plates, substantially as described, of a series of switches respectively connected with said sets of contact-plates and having contact-points, each of which is connected with a corresponding contact-point of a corresponding switch upon one or more other switch boards or tables.

5. The switch composed of a pivoted metallic switch-arm, provided with a contractile extension plate or piece, and a series of metal contact-points arranged in the path traversed by said extension plate or piece, when the same is extended only, substantially as described, 60 whereby said switch-arm may be readily moved to any contact-point without touching others in intermediate parts of its movement.

6. The switch composed of the pivoted metallic arm, the guided sliding metallic plate forced outward by a spring, and the metal 70 contact-points arranged in the path of said plate, substantially as and for the purpose set forth.

In testimony whereof I affix my signature in presence of two witnesses.

WILLIAM H. SAWYER.
